(57) **CLAIM**

The ornamental design for a neckband for wearable air conditioner as shown and described.

DESCRIPTION

1. Neckband for wearable air conditioner

1.1 : Perspective

1.2 : Front

1.3 : Back

1.4 : Left

1.5 : Right

1.6 : Top

1.7 : Bottom

1.8 : Front perspective view

1.9 : Perspective view 2

1.10 : Front view 2

1.11 : Back view 2

1.12 : Left view 2

1.13 : Right view 2

1.14 : Top view 2

1.15 : Bottom view 2

The broken lines depict portions of the neckband for wearable air conditioner that form no part of the claimed design;

(Continued)

this design is for a neckband for wearable air conditioner; as shown in reproduction 1.8, this design is used in combination with the front cover and the air conditioner body; as shown in reproductions 1.9 to 1.15, this design can be compactly folded for easy carrying; reproductions 1.1 to 1.8 show the state in which the claimed design has been unfolded, and reproductions 1.9 to 1.15 show the state in which the claimed design has been folded; reproduction 1.8 is a front perspective view showing the use state that the claimed design has been combined with the front cover and the air conditioner body.

1 Claim, 15 Drawing Sheets
